[57] CLAIM

The ornamental design for a sanding machine, as shown and described.

DESCRIPTION

FIG. 1 is a perspective view of one embodiment of the sanding machine showing my invention;
FIG. 2 is a front elevational view thereof;
FIG. 3 is a top plan view;
FIG. 4 is a rear elevational view;
FIG. 5 is an end elevational view;
FIG. 6 is a front elevational view of an alternative embodiment of the sanding machine showing my new design;
FIG. 7 is a top plan view of the embodiment shown in FIG. 6;
FIG. 8 is an end elevational view of the embodiment shown in FIG. 6;
FIG. 9 is a rear elevational view thereof; and,
FIG. 10 is an elevational view of the embodiment shown in FIG. 6 and illustrating the end opposite to that shown in FIG. 8.
